UNITED STATES PATENT OFFICE

2,443,356

FLEXIBLE JOINT FOR ARTIFICIAL LIMBS

John H. Mathis, Temple, Tex.

Application April 2, 1946, Serial No. 658,958

2 Claims. (Cl. 3—6)

1

This invention relates to an artificial limb, more particularly to the ankle joint therefor.

The primary object of the invention is to provide a flexible joint between the foot and shin members of an artificial leg of such a flexible nature that it will closely resemble the ankle joint of a human foot.

Another object is to provide a joint of such a character that it will absorb the shock of stepping or walking.

The invention will be clearly understood to those skilled in the art by reference to the accompanying drawings in which;

Figure 1 is a side elevation of the ankle and foot;

Figure 2 is a cross section of the heel as taken on line 2—2 of Figure 1.

Figure 3 is an end elevational view of the spring when not under pressure.

Figure 4 is the same as Figure 3, but showing the spring under pressure.

In the preferred form of my invention as illustrated, the shin member 1 and foot member 2 are connected through the medium of an intermediate block 3 by means of spring members connected to various portions of the leg and foot.

All of the springs are of the same general configuration, and a description of one will suffice to describe all of the springs.

Mounted on the transverse and horizontal axis and taking the place of the ankle bone of the human foot, is a spring element 4. Referring to Figure 3, it will be noted that the spring element 4 comprises a pair of plate-like bowed members 5 and 6 with their apices adjacent. The corresponding ends of the springs 5 and 6 lie between a central triangular-shaped member 7 and a slightly larger open triangular member 8 which overlies the ends of the members 5 and 6. Bolts 9 extend through the side legs of the triangular-shaped members 7 and 8 and the ends of the springs which lie against the side faces of the members 7 and 8 thus connecting the springs to the various parts comprising the artificial foot and leg. The openings through which the bolts 9 pass are all of the same size, so that the ends of the springs 5 and 6 are held against sliding. All stress and strain upon the springs 5 and 6 are taken up by their bending action. The springs 5 and 6 which have been described as bowed, are more nearly of a concavo-convex formation.

The spring element 4 connects the intermediate block 3 to the shin member 1, and, as stated, is mounted on a transverse and horizontal axis.

Spring elements 4' and 4'' connect the inter-

2

mediate block 3 to the foot 2 and are mounted in recesses provided in the two members. These elements are at right angles to the element 4 and to the front and rear of that element, but in different horizontal plane.

5 The intermediate block 3 is cut so that it will fit into the space formed in the foot portion 2. However, it is spaced from the shin member 1. Blocks 10 and 11 of rubber or the like, are placed 10 between the shin and intermediate block in the front and rear portions for the purpose of further reducing shock. A covering 12 of leather or the like, is placed over the front of the joint between the shin and intermediate block. However, the 15 covering may be placed over the entire joint so as to prevent injury to apparel which may be placed over the foot.

15 A V-shaped recess 13 is formed in the foot between the instep 14 and toe portion 15. This 20 recess has a V-shaped block of rubber 16 which is held therein by a flexible cover 17. The rubber block mounted between the instep and toe portions of the foot aid in giving flexibility to the foot when walking.

25 When in use, all of the springs 5 and 6 will flex to the approximate position shown in Figure 4. The springs 5 and 6 of the spring element 4 will bend on a line extending transversely and horizontally of the foot, while those of the elements 30 4' and 4'' will bend on a line extending longitudinally of the foot. When the wearer is walking and the foot and leg are at an acute angle to each other, the spring 5 will bend rearwardly while the spring 6 will have a tendency to 35 straighten. This same action will occur in the element 4' and 4'' depending upon the side to which the foot is rocked. Thus it will be seen that the three spring elements together with the rubber blocks 10 and 11 will remove all shock 40 incident with use of the leg.

45 By mounting the three springs in the manner shown, universal movement of the foot is allowed so that the ankle joint closely approximates that of the human foot. This will aid anyone in using the foot in walking on uneven surfaces.

While there is shown and described one form of the ankle joint, it is well understood by those skilled in the art that various changes may be made, which are within the scope of the appended claims.

I claim:

1. An artificial leg, a shin member and a foot member, a block interposed between the members, a spring connecting the shin member to the 55 block and a second spring at an angle to the

first-named spring, connecting the block to the foot member.

2. An artificial leg comprising shin and foot members, a block between the members, a spring connecting the shin member and the block, a second spring at right angles to the first spring connecting the block and foot member, each spring being of concavo-convex leaf formation mounted in brackets affixed to the members of the leg.
